PERFORATING MACHINE

Derk J. Oldenboom, Endicott, N. Y., assignor to
 International Business Machines Corporation,
 New York, N. Y., a corporation of New York

Application January 16, 1935, Serial No. 1,991

4 Claims. (Cl. 164—112)

This invention relates to certain new and useful improvements in perforating machines.

More particularly, this invention relates to perforating machines such as used in connection with perforation of cards used in the well known Hollerith system of accounting in which perforations are made on a card at selected index points, which are differentially located with respect to each other. Such a punch is shown in the Hollerith patent No. 682,197 issued September 10, 1901, which is designed to perforate the well known Hollerith card. In a punch of this type, each time a column is perforated the card carriage automatically steps ahead to present the next column for perforation. This method of operation is satisfactory whenever a regular prearranged form of perforating is to be used, particularly wherein all the information is punched on the card at one punching operation, which method largely predominates. There are however many instances of statistical analysis where information is acquired from time to time which must be perforated on cards which have already been perforated in many columns. An example of this type of analysis is used in hospitals and sanitaria where case histories of the individual patients are kept on cards. Codes are used for the various diseases and infirmities that are encountered and these codes are punched on the individual patient's card in accordance with whatever malady the patient is afflicted with.

The columns to be perforated therefore may vary considerably with each succeeding card, there being many columns in each card in which perforations are entirely omitted in which no two succeeding cards will require the same columns to be passed with no perforations. It is essential therefore that the machine for perforating these cards must be flexible for quickly locating the card at the proper column with ease and accuracy to be sure that when located the index points on the card will be in proper alignment with the punches.

It is an object of this invention to provide a perforating device in which the object to be perforated may be moved quickly to any position to be perforated.

Another object is to provide mechanism for locking the card into positive position in alignment with the punches.

A still further object is to provide locking mechanism for locking the machine against punching until the card is positively located for the punching operation.

Still another object is to provide a locking mechanism to render the perforating mechanism inoperative while the card carriage is being moved.

Various other objects and advantages of my invention will be obvious from the following particu-

lar description of one form of mechanism embodying the invention or from an inspection of the accompanying drawings; and the invention also constitutes certain new and novel features of the construction and combination of parts herein-after set forth and claimed. 5

In the drawings:

Fig. 1 is a plan view of the machine.

Fig. 2 is a partial longitudinal section showing the punching and locating mechanism. 10

Fig. 3 is an enlarged detailed cross section showing the locating and locking mechanism.

A base 10 is provided with a trough-like runway 11 of proper width to receive a card which may be moved longitudinally of the base. A slot 12 is provided in the base which runs its entire length and in which runs the card carrier. The card carrier comprises two end pieces 13 and 14 which are connected to a bar 15. The distance between the end pieces is substantially the length 15 of the card to be perforated. A small spring pressed member 16 is provided on the end-piece 13 to hold the card snugly against the end-piece 14 and thus hold it in fixed position. The bar 15 is provided with rollers 17 running on tracks 18 20 which are cut into the bar 19 fixed to the base of the machine. The end-piece 13 is connected to the bar 15 by a member 20 on which is mounted a handle 21 for the purpose of manually sliding the card carrier back and forth by virtue of the 25 rollers 17 and the roller 22 which rests on the base of the machine. The handle 21 is provided with a plunger 23 which is biased upwardly by a spring 24. The lower end of the plunger terminates adjacent the bottom of the slot 12 and is adapted to 30 cooperate with apertures 25 located in spaced relation to each other along the bottom of the slot 12. Adjacent these apertures on the underside of the bed plate opposite to the plunger 23 is a bail 26 extending longitudinally of the machine in line 35 with the centers of all the apertures and for a distance covering the length of travel of the end-piece 13.

This bail is supported at each end of an arm 27 fixed to a shaft 28 which is journaled in the supporting webs 29 of the base 10. Fixed to one end of the shaft 28 is an arm 30 which is biased in a counterclockwise direction as shown in Fig. 3 by a spring 31. The upper end of said arm is bifurcated and engages a pin 32 (Fig. 2) fixed to a comb 33 having slotted ends engaging a T-shaped member 34 mounted on the side frame of the key supporting structure 35 so that comb 33 is slidable back and forth transversely of the perforating device. 55

The perforator is provided with the usual well-known arrangement of punching mechanism such as shown in the previously mentioned Hollerith Patent No. 682,197 in which a series of punches 36 are slidably mounted in a frame member 37 and 60

are biased upwardly by springs 38 so that their upper ends abut a lever 39 which is fulcrumed at one end against an adjustable fulcrum 40. The levers 39 are held from side sway by a slotted plate in which each lever is positioned by a slot. The levers are of different length and terminate within the key supporting structure 35 in staggered relationship. The ends of the levers are bifurcated and engage a flat milled notch on the shafts 41 which are provided with keys 42 at their upper end suitably labeled with index numbers corresponding to the index numbers on the card to be perforated. The levers 39 are held upwardly by virtue of the springs 38.

15. Directly beneath the punches 36 and spaced therefrom a distance equal to the thickness of the material to be perforated is a die plate 43 provided with a die to receive each punch.

The comb 33 is provided with a series of upwardly extending teeth 44 which terminate directly underneath the levers 39 and the width of each tooth is substantially one-half the width of each lever. The levers 39 are provided with slots 45 extending substantially one-half the width of the levers and adjacent the ends of the teeth 44. In the normal position of the comb 33, as viewed in Fig. 3, the teeth 44 are positioned under the solid portion of the levers 39 to lock them up so that the keys 42 cannot be depressed. When 30 the comb is moved to the right the teeth are then located underneath the slots 45 which clear the teeth so as to permit the levers 39 to be depressed downwardly by their respective keys thereby thrusting the corresponding punch 36 35 into its die to effect a perforating operation.

Attached to the bar 19 are brackets 46 which support an index holder 47 adapted to receive an enlarged reproduction of a portion of the card to be perforated. The reproduction is substantially twice the size of the card to be perforated to facilitate the quick location of the card into the selected position.

Mounted on the member 20 is an arm 48 which is attached to an endless chain 49 running on sprockets 50 rotatably mounted on studs fixed to a bar 51 mounted on the brackets 46.

The left hand sprocket 50 as viewed in Fig. 1 is fixed to a sprocket 52 of substantially twice its diameter. An endless chain 53 engages this sprocket and is supported on its opposite end by a similar sprocket 54. An index pointer 55 is mounted on this chain and cooperates with the index mounted in the holder 47. Thus, due to the two-to-one ratio of the sprockets the index pointers will move twice the distance of the card carriage, since the movement of the card carriage carries the chain 49 with it rotating the sprockets 50 and therefore the sprocket 52 which moves the index pointer along the edge of the 60 index card.

In operating the machine, the operator places a card in the card carrier which is placed at the left position of its travel to receive the card, he then moves the carriage to the right until the 65 index pointer 55 points on the facsimile index the column which corresponds to the column of the card he desires to perforate. He then depresses the plunger 23 with his left hand causing the lower end of the plunger to enter the aperture 25 corresponding to the column which he is about to perforate. This definitely locates the column of the card under the row of punches 36

and the end of the plunger 23 strikes the bail 26 deflecting it downwardly and turning the shaft 28 in a clockwise direction, thereby turning the arm 30 clockwise about its supporting axis and moving the comb 33 to the right so that the teeth 44 now lie under the slots 45 so that the operator may select the key he desires. If for example the number 5 key is depressed, it will rock its corresponding lever 39 clockwise about its fulcrum 40 pressing its associated punch downwardly and through the 5 index point position in the selected column of the card to perforate the same.

The punches 36 are located transversely of the machine and parallel to the card columns, there being one punch for each index point position in 15 the column and spaced apart in accordance with the spacing of the index point positions.

The apertures 25 are spaced longitudinally of the card and correspond to the columns in the card. They are spaced apart in accordance with 20 the spacing of the columns. It is therefore impossible to perforate the card unless the plunger 23 enters one of these apertures to remove the comb 33 from blocking position and by virtue of this operation locking the carriage in position 25 whereby a column of the card will be located correctly under the row of punches.

While the fundamental novel features of the invention as applied to a single modification has been shown and described and pointed out it will 30 be understood that various omissions and substitutions and changes in the form and details of the device illustrated and in its operation may be made by those skilled in the art without departing from the spirit of the invention. I intend to be limited therefore only as indicated by the scope of the following claims.

What I claim is:—

1. In a perforating machine, a base, a punch support mounted on said base, a series of punches 40 mounted in said support, means for operating said punches, a card carrier slidable along said base to carry a card to the punches, manual means for freely sliding said card carrier back and forth and a device for inhibiting operation 45 of the punches while the card carrier is being manually moved in either direction.

2. In a perforating machine, a base, a series of punches supported by said base, means for operating said punches, a locking device for normally inhibiting operation of said punch operating means and manually operated common means for rendering all of said locking device ineffective to inhibit the operation of said punches.

3. In a perforating machine, a base, a series of 55 punches supported by said base, a series of depressible levers for operating said punches, a slideable member adjacent said levers normally positioned to prevent the depression of said levers and means to slide said member to another position 60 whereby said levers may be depressed.

4. A perforating machine having a series of punches supported on a base, depressible levers for operating said punches, a slideable member adjacent said levers for locking them in inoperative position, a bail connected with said slideable member, a card carrier slidable along said base to carry a card to the punches, and a depressible member mounted on said card carrier and adjacent said bail for moving said slideable member out 65 of locking position.

DERK J. OLDENBOOM.
